(57) **CLAIM**

An ornamental design for a fishing chair, as shown.

DESCRIPTION

FIG. 1 is a perspective view of the fishing chair.

FIG. 2 is an alternative perspective view of the chair of FIG. 1.

FIG. 3 is a left side view of the chair of FIG. 1; and,
FIG. 4 is a right side view of the chair of FIG. 1.

The broken lines shown in the drawing are for the purpose of illustrating environmental structure and form no part of the claimed design.

1 Claim, 4 Drawing Sheets(56)
